US0D1110746S

(12) **United States Design Patent** (10) **Patent No.:** **US D1,110,746 S**
(45) **Date of Patent:** **** Feb. 3, 2026**

(54) **DISPLAY DEVICE**

- (71) Applicant: **SAMSUNG DISPLAY CO., LTD.**, Yongin-si (KR)
- (72) Inventors: **Eui Ri Cho**, Suwon-si (KR); **Kee Hyun Nam**, Seoul (KR); **Duk-Woon Choi**, Hwaseong-si (KR); **Seung-Gyun Woo**, Hwaseong-si (KR); **Young-Su Kim**, Daegu (KR)
- (73) Assignee: **Samsung Display Co., Ltd.**, Yongin-si (KR)
- (**) Term: **15 Years**
- (21) Appl. No.: **29/927,023**
- (22) Filed: **Feb. 1, 2024**

Related U.S. Application Data

- (62) Division of application No. 29/756,301, filed on Oct. 27, 2020, now Pat. No. Des. 1,013,680.

(30) **Foreign Application Priority Data**

(57) **CLAIM**

The ornamental design for the display device, as shown and described.

DESCRIPTION

FIG. 1 is a front perspective view of the display device shown in an unfolded state;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIG. 8 is a front perspective view of the display device shown in a folded state;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof; and,

FIG. 15 is another front perspective view of the display device shown in the unfolded state with a stylus pen.

The broken lines shown in the drawings are for illustrative purposes only and form no part of the claimed design.

1 Claim, 15 Drawing Sheets
